DESIGN FOR A LAMP SHADE OR THE LIKE

Louis E. Lindenbaum, Brooklyn, N. Y.

Application March 27, 1946, Serial No. 128,006

Term of patent 7 years

(Cl. D48—16)

To all whom it may concern:

Be it known that I, Louis E. Lindenbaum, a citizen of the United States of America, residing at Brooklyn, in the county of Kings and State of New York, have invented a new, original, and ornamental Design for a Lamp Shade or the like, of which the following is a specification, reference being made to the accompanying drawing, forming a part thereof, in which

Fig. 1 is a perspective view of a lamp shade, or the like, showing my new design.

Fig. 2 is a front view of two complete repeats of my new design, taken at section designated by the numeral 2 in Fig. 1.

Fig. 3 is a cross-sectional view of my new design, taken on line 3—3 of Fig. 2.

Fig. 4 is a cross-sectional view of my new design, taken on line 4—4 of Fig. 2, and

Fig. 5 is a cross-sectional view of my new design, taken on line 5—5 of Fig. 2.

I claim:

The ornamental design for a lamp shade or the like, as shown.

LOUIS E. LINDENBAUM.
